CLAIM

We claim the ornamental design for a promotional display, as shown.

DESCRIPTION

FIG. 1 shows a front perspective view of our design for a promotional display;

FIG. 2 shows a front view thereof;

FIG. 3 shows a rear view thereof;

FIG. 4 shows a top view thereof;

FIG. 5 shows a bottom view thereof;

FIG. 6 shows a side view thereof; and,

FIG. 7 shows an opposite side view thereof.

The dashed lines in FIGS. 1–3 are for illustrative purposes only and do not form part of the claimed design.
